Surgical Vision, Inc.(57) **CLAIM**

We claim the ornamental design for a docking assembly, as shown and described.

DESCRIPTION

FIG. 1 is a perspective view of a docking assembly of the present application, mounted on one side of an ophthalmic intervention system shown in phantom;

FIG. 2 is a front view of the docking assembly;

FIG. 3 is a rear view of the docking assembly;

FIG. 4 is a right side view of the docking assembly;

FIG. 5 is a left side view of the docking assembly;

FIG. 6 is a top view of the docking assembly; and,

FIG. 7 is a bottom view of the docking assembly.

The broken lines show portions of the article which form no part of the claimed design.
